TRACK FOR TRACK LAYING WHEELS

Joseph Kuchar, Chicago, Ill., assignor to Forged-Trak Co., Chicago, Ill., a corporation of Delaware

Application May 6, 1932, Serial No. 609,607

3 Claims. (Cl. 305—10)

This invention relates to tracks for track laying wheels which are adapted to be laid on the ground to provide support for a vehicle, and to be raised continuously as the vehicle proceeds.

The invention particularly relates to tracks comprising a series of articulated track elements, adjacent track elements being adapted to be trussed one to the other so as to provide a beam or bridge which is rigid against displacement in one direction and which is flexible with respect to displacement in the opposite direction.

One of the objects of the invention is to provide an improved track.

A further object of the invention is to provide an improved track element.

A further object of the invention is to provide an improved assembled track member and an improved truss arm assembly.

Other objects, advantages and capabilities of the invention will hereinafter appear in the following description of a preferred embodiment thereof, taken in conjunction with the accompanying drawings, in which

Figure 1 is a side elevation of a truss wheel embodying my invention;

Fig. 2 is a fragmentary cross-sectional view, on a larger scale, taken on the line 2—2 of Fig. 1;

Fig. 3 is a plan view of the track, partly in section taken on the line 3—3 of Fig. 2;

Fig. 4 is a side elevation of a portion of the track, showing the construction thereof in greater detail than is shown in Fig. 1, and on a larger scale;

Fig. 5 is a sectional detail view taken on the line 5—5 of Fig. 3, and

Fig. 6 is an inverted plan detail taken on the line 6—6 of Fig. 5.

Referring to the drawings, the improved track 10 is shown as part of a truss wheel. This truss wheel comprises a beam 11 which is pivotally mounted on an axle 12 at its center. At either end the beam 11 carries bearings 13 for axles 14 which project outwardly from the beam at either side. Wheels 15 are keyed to the axle 14 at each end. The peripheries of the wheels 15 are adapted to engage with portions of the track, which provide a rail or support for said wheels in the manner hereinafter more fully described.

The track 10 is constituted by a continuous series of articulated elements 16 which are pivotally connected together so that the same may accommodate themselves around the wheels 15 in the manner shown in Fig. 1. Means are provided so that each track element may be trussed 55 to the adjacent track elements in such a man-

ner that the track is rigid when subjected to load in one direction and is flexible and readily bent in the other direction. The rigidity referred to is important in the portion of the track located below and between the two pairs of wheels 15, this portion acting as an inverted bridge and distributing over a large area the load applied by the axle 12 on the beam 11.

Each track element comprises a shoe plate 17 which may be formed of forged steel, rolled steel 18 or other suitable material. Each plate 17 may be provided with transverse grousers or ribs 18. At its forward and rearward edges the plate 17 is provided with curved surfaces which cooperate with complementary surfaces upon the adjacent 15 shoe plates in the manner shown in Figs. 1 and 4. On each side each shoe plate 17 has secured thereto a link element 19 which will now be described. The link element 19 preferably is a forging of the structure and configuration shown 20 in the drawings. The link element 19 is provided with hubs 20, 21 which are staggered transversely in the longitudinal direction so that the outer face of the hub 20 is in substantial longitudinal alignment with the inner face of the hub 21, as will more readily be understood with reference to Fig. 3. The hubs 20 and 21 are connected by a sloping vertical web 22 which is provided at its lower edge with a horizontal web 23 and at its upper edge with a horizontal web 24. The base 30 web 23 is provided on its upper side with bosses 25 which are provided with openings whereby the link element may be secured to the shoe plate by means of bolts 26.

The upper surface of the web 24 is machined 35 to provide a flat face 27. As will hereinafter appear, the flat faces 27 of the aligned links provide a track or rail for the wheels 15, which track or rail is laid down in front of the wheels and is taken up after the last wheels have passed over it. 40 On the inner side of the surface 27 the link element 19 is provided with an upwardly extending arm 28, which may suitably be a web of substantially triangular appearance. The arm 28 extends upwardly and is curved inwardly as shown 45 in Fig. 2 and is provided at its upper end or apex with a hub 29, the axis of which is preferably located half way between the hubs 20 and 21 and at a substantial distance thereabove.

The hubs 20 of each opposite pair of link elements 19 are connected by sleeves 31 which have a drive fit therein, and extend slightly therebeyond on either side so that in assembled condition said ends project into the hubs 21 which are counter-bored to receive them. Pins 32 have a drive fit in 55

the hubs 21 and extend through sleeves 31 in which they have a working fit.

The hubs 29 of each unitary pair of link elements 19 are connected by pins 33 which have a drive fit therein. The pins 33 are driven through openings in the ends of a large link 34 and two smaller links 35, the large link 34 being located in the center and the links 35 on each side thereof between the hubs 29. The large link 34 extends in one direction from the pin 33 and the links 35 extend in the opposite direction. The remote end of the link 34 is provided with a slot 36. The remote ends of the links 35 are provided with an opening 37 which receive a pin 38 with a drive fit. The pin 38 passes through the slot 36 of the link 34 of the adjacent track element.

On its under or outer side each link 35 is provided with a projection 39 and the link 34 is provided with lateral ears 40 which project into the path of the projections 39 and are adapted to engage therewith. It will readily be seen from Fig. 5 that when the track is below and between the pairs of wheels 15 the pins 38 are in the ends of the slots 36 remote from the pins 33 on which the links 34 are mounted. The effective lengths of the links 34 and 35 are such that the under portion of the track shown in Fig. 1 is effectively trussed and acts as an inverted bridge or beam so as to distribute the load upon a large area. 30 When the track begins to go around the wheels 15 the pins 33 approach each other and the pins 38 move somewhat towards the inner end of the slots 36 so that the projections 39 and ears 40 cause the links 34 and 35 to pivot about the pins 38, these pins moving downwardly or outwardly in the manner shown in Fig. 1.

In assembling the track two opposite link elements 19 are placed on either side of a sleeve or bushing 31 and are pushed inwardly so as to enter the bushing into the hubs 20 so as to project therebeyond to the desired extent. A pin 32 is then passed through the sleeve 31 and a further pair of opposite links 19 are then applied to the assembly with the hubs 21 in alignment with the hubs 20 of the assembly, and with their hubs 20 in alignment with a further sleeve 31. The last said links are then pressed inwardly so as to enter the last said sleeve 31 into their hubs 20 so as to project therefrom at each end and so as to press their hubs 21 on the ends of the pin 32 so as to bring the projecting ends of the first said sleeve 31 into the counterbores of the hubs 21.

This manner of assembly is continued until a track of desired length has been assembled. The link elements 19 are bolted to the shoe plate 17 at any time after their assembly upon the sleeves 31 and pins 32. The links 34 and 35 may be assembled in units by pressing two links 35 onto a pin 38 which is first passed through the slot 36 of a link 34. The link units 34, 35 may be assembled on the track simultaneously with or subsequent to the assembly of the link elements 19 upon the sleeves 31 and pins 32. That is during this assembly the link elements 19 may be pressed inwardly upon a pin 33 which is first passed through the openings in a pair of links 35 of one link unit and the opening in the link 34 of another link unit, or the link units may be located with their openings in alignment with the hubs 29 and the pin 33 forced inwardly therethrough from one side. It is obvious that the manner of assembly may be modified in various ways and that the links 34, 35 and the pins 33 may be removed and replaced without disassembling the remainder of the track. The sleeve 30' at the extremity of the

track is shorter than the sleeves 31 so that it does no project beyond the outer faces of the hubs 20. In applying the track to the wheels 15 rings 41 are placed in the counterbores of the hubs 21 at the extremity of the track and the hubs 20 are slipped in between the hubs 21. A pin 31' is slipped through the aligned hubs 20 and 21 and through the sleeve 30', the pin 31' having a working fit in the hubs 21. To maintain the pin 31' in position cotter pins 42 are passed therethrough as shown in Figs. 3 and 4. The truss elements are connected in series by passing a pin 33' through the hubs 29 of one of the extreme track elements so as to pass through the openings in links 35 and links 34 of adjacent truss link units. The pin 33' is slightly smaller than the pins 33 so it may pass freely through the hubs 29. The pin 33' may be held in position by cotter pins 43 which we have passed through the hubs 29 and suitable openings in the pins 33'.

It will readily be understood that I have provided a track which can be easily applied to and removed from the wheels 15 and which can readily be repaired by replacement of parts without disassembling the complete track. This manner of repair is particularly applicable to the links 34 and 35 and to the pins 33 and 38 which take the most of the wear. However, it is also applicable to other portions of the track, for example the shoe plate 17 may very easily be removed and replaced when wear or injury renders it necessary.

Although the invention has been described in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A track comprising a series of track elements, each element comprising a shoe plate, a pair of link elements bolted thereto, pins and bushings having a pressed fit in the link elements connecting each pair of links together, the pins extending through the bushings to connect links of the track pivotally together in series, an arm extending inwardly from each link element, means having a pressed fit in said arms, and links pivotally mounted thereon and extending therefrom in both directions, said links being secured to the links of the adjacent track elements so as to permit relative pivotal movement.

2. A track comprising a series of track elements, each element comprising a shoe plate, a pair of link elements bolted thereto, said link elements being provided with transverse hubs out of longitudinal alignment, pins and bushings having a pressed fit in said hubs, the pin of one track element extending through the bushing of an adjacent track element securing the link elements of the track elements pivotally together in series, truss arms extending inwardly from said link elements and provided at their upper end with hubs, transverse pins having a pressed fit in said hubs, links pivotally mounted on said pins and extending in both directions therefrom, and pins having a pressed fit in certain of said links and a working fit in the other links connecting said links together in series around the track.

3. A track comprising a series of track elements, each element comprising a shoe plate, a pair of link elements bolted thereto, said link ele-

ments being provided with transverse hubs located out of longitudinal alignment, a sleeve having a pressed fit in a pair of said hubs, a pin having a pressed fit in the other pair of hubs 5 and extending with a working fit through the sleeve of an adjacent track element, an inwardly extending truss arm carried by each link element provided at its upper end with a hub, pins having a pressed fit in each of said hubs connecting each pair of truss arms together, a link 10 pivotally mounted on each of said pins and ex-

tending therefrom in one direction, said link being provided with a slotted end, a pair of links, one mounted on each side of the first said link and pivotally mounted on said pins, said links being provided at their ends with openings, pins 5 having a drive fit in said openings and extending through the slot of a link of the adjacent track element, and abutments on said links adapted to cause the same to break outwardly when the track is bent. 10

JOSEPH KUCHAR.
